UNITED STATES PATENT OFFICE.

FREDERICK C. THIELSCHER, OF BOSTON, MASSACHUSETTS.

APPARATUS FOR FEEDING SHEETS OF PAPER.

SPECIFICATION forming part of Letters Patent No. 295,955, dated April 1, 1884.

Application filed February 13, 1883. (No model.)

To all whom it may concern:

Be it known that I, FREDERICK C. THIELSCHER, of Boston, county of Suffolk, State of Massachusetts, have invented an Improvement 5 in Apparatus for Feeding Sheets of Paper, of which the following description, in connection with the accompanying drawings, is a specification, like letters on the drawings representing like parts.

10 This invention has for its object the production of an efficient apparatus by which to automatically feed sheets of paper singly from a pile to another place where it is desired to use them, and is especially adapted to automatically place thin sheets of paper between 15 printed cards or sheets as delivered from a lithographic press of usual construction; but it will be understood that my mechanism may be used in other places and for other purposes—as, for instance, to feed sheets of paper to a press.

The apparatus to be herein described may be divided into three parts—viz., mechanism for supporting the pile of sheets, picking-up 25 mechanism to lift sheets singly, and feeding mechanism to take each sheet from the picking-up mechanism, carry the same forward, and discharge or drop it. The supporting mechanism for the pile of sheets consists of a 30 bed on which the pile of sheets rests, means to raise and lower the bed as each sheet is picked up, and means to adjust the bed automatically to the decreasing thickness of the pile of sheets. The picking-up mechanism 35 includes two or more suction-tubes connected by suitable pipes with a suitable exhaust-chamber or air-pump, and a valve between the suction-tubes and exhaust-chamber or air-pump, to permit the top sheet of the pile to be retained in contact with or to be held by the tubes, as may be desired. The feeding mechanism includes two pairs of nippers—one for each edge of the sheet near its leading end—a carriage to move the nippers forward, 40 and means to open and close the nippers so that they grasp and release each sheet at the proper times. When the carriage arrives at its forward position, the nippers are opened automatically to discharge the sheet held by them, and they are then locked and held open as the carriage is moved back, during which 45 times the supporting-table for the pile of

55 sheets is raised to place the uppermost sheet of the pile against the ends of the suction-tubes of the picking-up mechanism, and the valve between the said tubes and the exhaust-chamber or air-pump is then opened, causing the uppermost sheet to adhere to the said tubes, from which the air is then exhausted, and the table and pile of sheets descend, leaving the sheet held by the tubes. The open 60 nippers, in their backward travel, pass over the end of the sheet thus held by the tubes of the picking-up mechanism above the pile of sheets, and, having reached a position opposite the said tubes, are closed upon the opposite edges of the sheet of paper held by the tubes, and the valve between the tubes and the exhausted receiver or air-pump is then closed, so that the tubes cease to hold the sheet. 70 The nippers, having been closed upon the sheet, are moved forward, and, reaching their forward position, are opened automatically to discharge the sheet held by them on a suitable table, or on another sheet at the top of a 75 pile of sheets. If my apparatus is to be employed to place thin sheets of paper in succession between printed sheets or cards as they are delivered from a lithographic or other press, the apparatus will be located at the rear 80 side of the said press, so that the nippers may travel forward over the delivery-table of the said press.

Figure 1 represents in side elevation a paper-feeding apparatus embodying my invention, the nippers being open, the dotted lines under the nippers being intended to represent the delivery bed or table at the rear of a lithographic press of usual construction. Fig. 2 is a front elevation of Fig. 1. Fig. 3 is a detail in side elevation of the mechanism instrumental in moving the paper-supporting table; Fig. 4, a section of Fig. 3 on the dotted line x ; Fig. 5, a section of Fig. 4 on the dotted line x' ; Fig. 6, a detail of the npper-carrying rods, and means to move them to open the npper. Fig. 7 is a detail to be referred to; Fig. 8, a plan view of one member of the nppers, to be referred to; and Fig. 9, a section on line x'' ; Fig. 1, of the latch for holding the nppers open after they have delivered a sheet until the proper time for them to close upon a succeeding sheet to be fed.

The frame-work A, of suitable shape to sus-

tain the working parts, has a main shaft, B, provided, as herein shown, with a crank, C, a disk, b^3 , provided with a cam, b^{12} , and a cam, a^9 . The table L (shown in dotted lines 5 only in Fig. 1) is supposed to be the delivery-table of a lithographic press, and each printed sheet delivered thereon must be separated from a succeeding one by a thinner sheet, to obviate blurring, &c. The sheet-supporting mechanism is composed of a bed, a , having a threaded stem, a' , acted upon by a worm-gear, a^2 , in turn rotated by a worm, a^3 . The worm-gear a^2 and worm a^3 are both mounted so as to turn in a bracket, a^4 , attached to the under side of 10 a plate, a^5 , pivoted at a^6 , and having a leg, a^7 , provided with a roller, a^8 , acted upon by the cam a^9 on the main shaft B. The worm a^3 has connected with it a friction-disk, b , which is acted upon and rotated intermittently by a 15 friction-pawl, b^2 , attached to a pawl-carrier, b^3 , mounted on the journal of the said worm. The pawl is made to move the friction-wheel at each descent of the plate a^5 , it then striking the adjusting-screw b^4 . The screw b^4 may 20 be so adjusted as to cause the bed a to be raised to maintain the uppermost sheet of the pile of sheets at a certain level, so that as the bed is raised to force the said sheet against the lower ends of the suction-tubes b^6 of the 25 picking device there may always be a uniformity of action, notwithstanding the variation in the height of the pile of sheets. The bed a will have at its sides and ends suitable 30 projections, guards, or pins, 10 12, to prevent the escape of the sheets of paper, except when 35 lifted by the picking-up mechanism.

Instead of the particular means herein shown to adjust the position of the bed a vertically, and the said pins 10 12, I may use any other 40 well-known and equivalent devices common to envelope-machines; and instead of raising the plate a^5 and the pile of sheets as each sheet is to be held by the picking-up mechanism, I desire it to be understood that the plate 45 a^5 may be stationary and tubes b^6 of the picking-up mechanism may be raised and lowered, as in envelope-feeding machines, where the blanks are picked up by suction. The picking-up mechanism is composed, essentially, of 50 the tubes b^6 , before referred to, they having preferably india-rubber mouth-pieces at their lower ends, and being connected with a pipe, b^7 , the open end of which terminates in a valve-box, b^8 , having a valve, b^9 , the lower end of 55 the said valve-box being connected by suitable pipes with any suitable vacuum-chamber or exhausting device, so that when the valve b^9 is drawn out in the direction of the arrow on its stem in Fig. 1 air will be drawn into the 60 tubes b^6 in the direction of the arrow, causing them to adhere to the top sheet of the pile of sheets of paper, which top sheet has been lifted against the lower ends of the tubes by 65 the supporting-table a , before referred to. The valve b^9 is operated in one direction by a lever, b^{10} , acted upon by the cam b^{12} on the disk b^3 ,

and in the opposite direction by the spring b^{14} , the spring closing the valve immediately after the nippers, to be described, have grasped the sheet of paper picked up and held by the tubes, so that the draft of air no longer acts to hold the sheet. The nippers are composed of the upper members, c , and lower members, c' . 70

The nippers at each side of the machine being alike, I need specifically describe but one of them, which I will now do. The upper member, c , is connected with a rigid arm attached to a slide-rod, c^3 , connected with an upright, c^4 , adjustably attached by a screw, 80 c^5 , with a cross-bar of an adjustable carriage, c^6 , having slide-bars which are fitted to guide-ways c^7 . (Shown in Fig. 2.) The carriage c^6 is connected by link E and bolt D with the crank C, attached to the main shaft B, and as the said shaft is rotated the carriage and its rods and connected nippers are reciprocated backward and forward. The rod c^3 is extended through a guide, c^8 , made adjustable toward and from the center of the machine in 85 bearings c^9 . In order to adapt the rods c^3 and their nippers to different widths of sheets of paper to be delivered, the rod c^3 has hangers c^0 c^{10} , adjustably connected thereto by screws 3, and a hanger, c^{12} , fast thereon at its 90 forward end. These hangers receive and form 95 bearings for the nipper-rocking rod d , upon the forward end of which is fixed the nipper member c' .

The nipper-carrying rod d has placed about 100 it a spiral spring, d' , one end of which is connected with the hanger c^0 , and the other with an adjustable collar, d^2 , fixed upon the rod d , the said spring acting normally to move the nipper member c' in the arc of a circle toward 105 the fixed nipper c . The rod d also carries a collar, d^3 , provided with a pin, d^4 , which, as the rod is moved in the direction of the arrow on it, strikes the inclined plate d^5 , fixed with relation to the frame-work A, and causes the 110 nipper member c' to be turned down away from the nipper member c when it is desired to discharge from between the nippers the sheet of paper held by them. The pin d^4 will usually be provided with a friction-roller. 115 When the nippers are so opened, the latch e' , or holder for the lower nipper, c' , enters a notch in a collar, e , fast upon the rod d , and thereafter the nippers are held open or separated until in the backward movement of the 120 rods c^3 the end of the latch strikes the end of the latch-opener e^2 , fixed with relation to the carriage, when the latch is lifted, permitting the spring d' to turn the rod d and close the nipper member c' upon the under side of 125 the sheet of paper and against the stationary nipper c , the said nippers then occupying a position at the side of one of the tubes b^6 of the picking-up mechanism.

As described, it will be noticed that the 130 nippers are closed at the proper times to grasp the sheet held by the tubes of the picking-up

device, are then moved forward, and on arriving in proper position are opened automatically to discharge the sheet held by them, and are held open while being moved backward in 5 position over the edges of a succeeding sheet picked up by the tubes and held lifted above the pile of sheets, ready to be delivered to the nippers and carried forward by them.

I do not broadly claim suction-tubes to pick 10 up a sheet, nor do I broadly claim a nipper to engage a sheet of paper. The rear end of the nipper member *c* is provided with an upwardly-turned lip, *c*²⁰, as shown in Figs. 1 and 8, to enable it to pass above the end of the 15 sheet held by the suction-tubes.

I claim—

1. In a paper-feeding machine, the bed *a*, to support sheets of paper in a pile, the plate *a*⁵, by which it is carried, and means, substantially as described, to lift the said plate and bed, combined with the suction-tubes to pick up and hold the sheets, one by one, from the pile, the two pairs of nippers arranged at opposite sides of the bed, means, as specified, to 25 actuate said nippers to engage the side edges of the lifted sheet held by the suction-tube, and means, as set forth, to reciprocate said nippers and their actuating devices to convey such sheet to the place of deposit and return 30 for another sheet, substantially as shown and described.

2. The nipper member *c* and the slide-rod and its attached hangers, combined with the 35 rocking rod and its connected nipper member *c*', substantially as described.

3. The nipper member *c*, its slide-rod, the attached hangers, the rod *d*, supported in said hangers, and the nipper member *c*' on said 40 rocking rod, combined with the pin or projection *d*⁴ and a stationary incline with which in the reciprocation of the slide-rod the projection comes in contact to rock the rod *d* to open the nippers; substantially as described.

4. The nipper member *c*, its slide-rod, the

attached hangers, the rod *d*, supported in said 45 hangers, and the nipper member *c*' on said rocking rod, combined with the pin or projection *d*⁴, a stationary incline with which in the reciprocation of the slide-rod the projection comes in contact to rock the rod *d* to open 50 the nippers, and the spring *d*', connecting the rod *d* and one of the hangers, to automatically and normally close the nippers, substantially as described.

5. The combination, substantially as shown 55 and described, of the rod *c*³, rocking rod *d*, and nipper members *c* *c*', with the notched collar *e* and latch *e*'.

6. The combination, substantially as shown 60 and described, of the sliding rod *c*³, the connected rocking rod *d*, and the nipper members *c* *c*', with the notched collar *e*, latch *e*', and latch-opener *e*², as and for the purpose described.

7. Two pairs of rods, *c*³ and *d*, and connected 65 nipper members *c* *c*', combined with adjustable guides in which the said rods are reciprocated, to permit the nippers to be adjusted to adapt them to sheets of paper of different widths, substantially as described. 70

8. The slide-rods *c*³ and *d* and nippers *c* *c*', combined with a reciprocating carriage for moving the said rods, and with means, substantially as described, for rocking the rod *d* to open and close the said nippers, as set forth. 75

9. The bed *a*, the plate *a*⁵, by which it is carried, and means, substantially as described, to lift the said plate and bed, combined with the suction-tubes and two pairs of nippers, *c* *c*', to operate as set forth. 80

In testimony whereof I have signed my name to this specification in the presence of two subscribing witnesses.

FREDERICK C. THIELSCHER.
